UNITED STATES PATENT OFFICE.

GUSTAV BERNHARD PETSCHE, OF PHILADELPHIA, PENNSYLVANIA, ASSIGNOR TO SOUTHWARK FOUNDRY & MACHINE COMPANY, OF PHILADELPHIA, PENNSYLVANIA, A CORPORATION OF PENNSYLVANIA.

GAS-ACTUATED BLOWING-ENGINE OR COMPRESSOR.

No. 894,047.

Specification of Letters Patent.

Patented July 21, 1908.

Application filed September 3, 1903. Serial No. 171,764.

To all whom it may concern:

Be it known that I, GUSTAV BERNHARD PETSCHE, a subject of the Emperor of Germany, residing in the city and county of Philadelphia, in the State of Pennsylvania, have invented certain new and useful Improvements in Gas-Actuated Blowing-Engines or Compressors, of which the following is a true and exact description, reference being had to the accompanying drawings, which form a part thereof.

My invention relates to compressors or blowing engines which are actuated by gas engines, and has for its object to provide a governor system for the control of the gas engine by which it is especially adapted for use in connection with the compressor.

In blowing engines which are actuated by gas engines, and in which the power is less flexible than where the engine is actuated by a steam engine, the rise in pressure in the receiver of the blowing engine has given rise to considerable trouble, and, to enable the gas engine to work under such conditions, the plan has been devised of so varying the motions of the air admission valve of the compressor that, when the pressure in the receiver increases above normal, the closing of the admission valve is delayed so that the quantity of air compressed at each stroke of the engine is diminished. This, however, obviously diminishes the efficiency of the engine, and it is exceedingly desirable that some means should be provided by which, under similar conditions, the gas engine will be capable of working with greater power, and it is particularly to secure this desirable result that my invention is intended. The particular form disclosed of the novel means for accomplishing this result which I have devised comprises the combination in an engine of the kind described of a cylinder adapted to contain a non-compressible fluid having non-return entrance ports and independent exit ports controlled by means normally closing both but capable of opening either at will, the piston of said fluid cylinder being connected with a portion of the apparatus which, in the operation thereof, has communicated to it alternating impulses in different directions, the said part or element of the machine being held stationary against such impulses by the fluid in the cylinder, and permitted to move only when one or the

other of the exhaust ports thereof are open, and the said movable part being connected in turn, to other elements of the mechanism by which the desired variations in the operation of the engine are secured, for instance, the mechanism which varies the timing of the inlet valve of the compressor,—the mechanism which varies the admission of the explosive mixture to the gas engine and the mechanism which regulates the flow of water through the water jacket of the gas engine.

The nature of my improvements will be best understood as described in connection with the drawings in which they are illustrated, and in which—

Figure 1, is a side elevation of a blowing engine embodying my improvements, Fig. 2, being a longitudinal section through the gas engine cylinder. Fig. 3, is an end elevation on an enlarged scale, showing the head of the compression cylinder and parts connected therewith, and also the governor for the gas engine. Fig. 4, is an end elevation on a somewhat larger scale of the fluid cylinder and its connections. Fig. 5, a side elevation thereof. Fig. 6, a cross-section through the fluid cylinder on the irregular line 6—6 of Fig. 8. Fig. 7, a cross section through the fluid cylinder on the line 7—7 of Fig. 8. Fig. 8, is a plan view of the fluid cylinder. Fig. 9, is a side elevation on an enlarged scale of the rear end of the gas engine cylinder and its connections. Fig. 10, is a cross-section, taken partly through the admission port of the gas engine, and partly through the water conduit leading into the front end of the cylinder, approximately on the irregular line indicated at 9—9 in Fig. 1, the view also showing the governor and valve actuating mechanism connected with the admission valve. Fig. 11, is a cross-section through the exhaust port of the gas engine taken approximately on the line 11—11 of Fig. 9, showing the exhaust valve actuating mechanism. Fig. 12, is a perspective view showing the gear connections for actuating the governor.

A, indicates the base of the machine, B, the gas engine cylinder, which is provided with a water jacket B', and separable head B", the jackets in the cylinder and head being connected by conduit B'; B⁴, indicating the water inlet passage leading to the water jacket and B⁵, the exit passage.

B^6 , is the exhaust port and B^7 , the entrance port to the engine.

C , is the piston of the gas engine which connects through piston rod C' , with the compressing piston, not shown, of the blowing engine and through bearing pin C^2 , with a connecting rod C^3 , which is coupled to the crank arm D , of the shaft D^2 , on which is secured the fly wheel D' .

E , indicates the compressing cylinder, E' , E' , the receivers at each end of the cylinder which are connected with a common receiver E^2 .

At E^2 , I have indicated an actuating cylinder, such as commonly employed to open the delivery valves of the engine blowing cylinder, E^4 , E^4 , indicating connecting rods which are employed to close the said valves and which, as shown, are connected with crank arms E^6 , secured on shafts E^8 , which, in turn, are connected through links E^7 , to eccentrics E^8 , secured on the eccentric shaft E^9 .

At E^9 , I have indicated one of the admission valves of the blowing engine, these valves being actuated through their stems F , and crosshead guides F' , which are connected by links F^2 , with links F^3 , the lower ends of said links being connected by extending straps F^4 , with the eccentrics on the shaft F^5 , the upper ends being guided by links F^6 , supported on pivots F^7 , which are supported, in turn, on the short arms F^8 , of levers F^9 , F^{10} , pivoted at F^7 , and it will be understood that any motion of the lever arms F^9 , F^{10} , will materially modify the motion imparted to the links F^3 , and through them to the admission valves of the engine, and it is also obvious that at every rotation of the cam shaft alternating impulses tending to move the levers F^9 , F^{10} , will be communicated thereto through the link F^2 .

F^9 , is a piston rod connected to the outer end of the lever arm F^8 , and to the piston G , see Fig. 6, which moves in the fluid cylinder G' , said cylinder having entrance ports leading into the top and bottom, the bottom port being indicated at G^2 , and each provided with valves as indicated at G^3 , G^4 . The cylinder is also provided at each end with exit ports, indicated at G^5 , and G^6 , which, in the construction shown, both open into the cylindrical valve chamber G^7 , in which moves the cylindrical valve G^8 , which is of such size as to normally close both ports while capable of opening either one according as it is moved up or down. I also provide the cylinder, as shown, see especially Fig. 7, with a dash pot chamber G^9 , having ports G^{10} , G^{11} , connecting its top and bottom and in which is situated a flow regulating valve indicated at G^{12} .

G^{12} , is the piston moving in the dash pot cylinder.

H , is a link connected with the lever arm F^8 , and with one end of the lever H' , from an

intermediate point of which extends the link H^2 , which actuates the valve G^8 , and from the other end of which extends piston rod H^3 , which is connected with dash pot piston G^{13} , and also to upwardly extending piston rod H^4 , which extends through a stuffingbox in the bottom I' , of a cylinder I , and connects with a piston H^5 , of said cylinder. The head I^2 , of the cylinder I , is adjustable, and the spring I^3 , is situated between the piston H^5 and the head I^2 .

I^4 , is a fluid conduit leading into the bottom of the cylinder I , from the receiver E' , of the compressor.

J , is a connecting rod extending from the lever F^8 , to a lever arm J' , secured to the rock shaft J^2 , which rock shaft has also secured to it the lever arm J^3 , which, by rods J^4 , connects with an adjustable weight J^5 , moving on the lever L^2 of the gas engine governor. Still another lever arm J^6 , extends from the shaft J^2 , and connects, through a rod J^7 , with a regulating valve J^8 , which controls the flow of water through the port B^4 of the water jacket of the gas engine. The power to actuate the valves and connections is, as shown, derived from the shaft D^2 , see Fig. 1, which has secured to it the bevel gear K , which drives the bevel gear K' , the shaft K^2 , which, through gear wheel K^3 , and gear K^4 , drives cam shaft f^1 , the shaft K^2 , also driving, through gears K^6 and K^7 , the eccentric shaft K^8 , by which motion is imparted to the valves of the gas engine.

L , L' , indicate the rotating weights of the governor, the sliding weight being indicated at L^2 , K^1 , indicating the governor spindle which is actuated through the skew gears K^{10} , and K^9 , from the shaft K^8 ; a lever arm L^2 , is connected to move with the weight L^1 , and has resting upon it the adjustable weight J^5 , already mentioned. It is, as shown, provided with a dash pot cylinder L^4 , in which is secured the usual dash pot piston connected with lever arm L^2 , by rod L^3 , see Fig. 10. The end of the lever arm L^2 , connects by rod L^5 , with the lever arm M , pivoted at M^2 , and carrying the trip lever M' .

N , is an eccentric on the shaft K^8 , the motion of which is communicated by eccentric strap N' , and a link N^2 , to an oscillating lever N^3 , pivoted at N^4 , and carrying the valve hook N^5 , having an upwardly extending arm N^6 , which in the upward motion of the hook comes in contact with the stop lever M' . The hook engages and operates the lever arm O , also pivoted at N^4 , and secured to the oscillating cam O' , which, in turn, communicates motion to the cam lever O^2 , indicated, and through it the valve stem P , and sleeve P' , which move together, the stem supporting the valve P^2 , controlling the port of the air passage Q , and the sleeve supporting the valve P^3 , controlling the port of the casing gas passage Q' . The other eccentric R , see

Fig. 11, communicates motion through strap R⁷, and link R⁸, to rock lever R⁹, to which is secured the cam R¹⁰, which communicates motion to the cam lever R¹¹, pivoted at R¹², and connected with the stem S, of the exhaust valve S', which controls the exit port Q¹³.

The device for operating and for varying the motions of the admission valve of the compressor consisting of the link F¹⁴, having its upper end guided on an adjustable support such as f¹⁵, forms the subject matter of my application for Letters Patent, filed, April 22nd 1903—Serial Number 153,775 though in my said former application the adjustment of the bearing f¹⁶, was accomplished by means acting directly upon it and independent of the impulses given to it by the motions of the link F¹⁴. In my other application filed September 3rd 1903 Serial Number 171,763 I have shown and described a device consisting of the fluid cylinder G', and the piston G, said piston being attached to a movable part of an engine, which movable part is, in the operation of the engine, given alternating impulses in opposite directions and connected to vary the operations of one or more elements of the engine. As in the present case, the connection is with the lever F¹⁸, from which connections are made to the link F¹⁴, the adjustable weight J, on the gas engine governor, and the gate or valve controlling the cooling water which jackets the gas engine cylinder, and my said last mentioned application claims broadly the employment of the cylinder for such purposes as also the use of a governing device to control the exit valve of the fluid cylinder G', as in the present case it is controlled by the pressure cylinder I.

It will be understood that under normal conditions of pressure the valve G¹⁸, closes both of the exit ports of the cylinder G', the piston G, being held stationary in the cylinder and through its connection with the lever F¹⁸, holding such lever stationary, as also the attached bearing f¹⁶, on the short arm of that lever. Under these conditions the motion of the link F¹⁴, and the attached admission valve is constant, the weight J¹⁵, remains in a fixed position on the lever L¹⁷, and the gate or valve J¹⁸, remains in a fixed position in the conduit B¹⁹, consequently the operation of the gas engine is controlled solely by the governor L, which, through the described mechanism, determines the cut off of the valve, admitting air and gas to the cylinder, while the cooling water passing through the jacket of the gas engine cylinder is of constant volume. In case, however the pressure in the receiver E', of the compressor rises above normal, the said pressure is communicated through the pipe I', to the cylinder I, and moves the piston H²⁰, up in the cylinder, until the increased pressure beneath the piston is balanced by the compres-

sion of the spring I²¹. This upward motion of the piston carries with it the attached end of the lever H', which, turning on its attachment to the link H, raises, through rod H²², the valve G¹⁸, opening the lower exit port of the cylinder G'. The piston G, is then free to move down under the recurring downward impulses communicated to the lever F¹⁸, by its connection with the link F¹⁴, fluid flowing in through the upper admission port of the cylinder G', at each downward movement and the motion continuing until the corresponding downward movement of the link H, causes the valve G¹⁸, to again close the lower exit port when the piston G, and connected parts are again brought to a stationary position; but the downward motion of the lever F¹⁸, is of course accompanied by an upward motion of the upper lever arm F¹⁴, and bearing pin f¹⁶, in consequence of which the motion of the link F¹⁴, is so varied as to defer the closing of the admission valve connected with the valve stem F, so that a smaller volume of air is compressed at each stroke of the piston in the compressing cylinder and consequently the gas engine running with uniform power is enabled to compress this diminished quantity of air to the increased pressure temporarily existing in the receiver, but it is evident that this capacity of the gas engine to work under the abnormal conditions mentioned is secured by serious loss in the volume of air compressed and therefore I provide for so deferring the cut off of the gas engine admission valves that under these conditions a larger quantity of the expansive mixture is admitted to the cylinder and its capacity for work thereby increased. This is accomplished by the action of the downwardly moving lever F¹⁸, on the rock shaft J²³, shifting said rock shaft so that through its connection J²⁴, and link J²⁵, it moves the adjustable weight J¹⁵, out toward the outer end of the lever L¹⁷, thus increasing the load on the governor L, and insuring that under the same speed the stop lever M²⁶, will be retracted so as to defer its contact with the hook catch N²⁷, that is, so that the valves P²⁸, and P²⁹, will remain open longer and admit a greater volume of the expansive gases to the engine cylinder. In effect, this increases the speed of the engine and makes it desirable to provide an increased quantity of water for cooling the cylinder, and the same motion of the rock shaft J²³, which affects the cut off of the gas engine retracts the valve J¹⁸, increasing the flow of water through the water jacket. Of course where the supply of water to the water jacket is directly controlled by the speed of piston movement this governing device would be unnecessary.

It will readily be seen that when the pressure in the receiver of the engine and in the cylinder I, falls, the effect upon the exit valve of the cylinder G', will be directly the

reverse of that described, the valve moving downward to open the upper exit port whereupon the impulses communicated to the lever F⁸, will cause it and the piston G, to move upward, and will effect the shifting of the parts connected to the lever F⁸, in the opposite direction to that already described.

Having now described my invention, what I claim as new and desire to secure by Letters

10 Patent is

1. The combination with an air compressor or blower and a gas engine connected to actuate it, of an inertia governor regulating the admission to the gas engine, and means actuated through the varying pressures in the receiver of the compressor for varying the action of said governor to thereby increase the speed of the engine as the pressure in the receiver rises and to decrease 20 the speed of the engine as the pressure in the receiver falls.

2. The combination with an air compressor or blower and a gas engine connected to actuate it, of an inertia governor regulating the speed of the engine, and means responsive to variations in pressure in the receiver of the compressor for varying the action of the governor to thereby cause it to increase the speed of the engine as the pressure in the receiver rises and to decrease the speed of the engine as the pressure in the receiver falls.

3. The combination with an air compressor or blower and a gas engine connected to actuate it, of a valve controlling the admission of air to the compressor, a speed governor for regulating the admission to the gas engine, means responsive to variations of pressure in the receiver of the compressor for directly actuating said admission valve to vary the air admitted by it inversely as the pressure in the receiver varies, and means directly responsive to the condition of the admission valve for varying the action of the speed governor to vary the admission to the gas engine directly as the pressure in the receiver varies.

4. In combination with an air compressor or blower and a gas engine connected to actuate it, and having a water jacket, a valve regulating the flow of water through the jacket of the engine, a governor regulating the admission of fuel to the gas engine, and means actuated through the varying pressures in the receiver of the compressor for varying the action of said governor and shifting the water regulating valve.

5. In combination with an air compressor or blower and a gas engine connected to actuate it, means for varying the movements of the valves admitting air to the compressor, a governor regulating the admission to the gas engine, and means actuated through the varying pressures in the receiver of the compressor and acting to vary the motions of the

air admission valves of the compressor so as to diminish the quantity of air to be compressed at each stroke as the pressure increases, said pressure controlled means also acting to vary the action of the governor so as to increase the admission to the gas engine as the pressure increases.

6. In combination with an air compressor or blower and a gas engine connected to actuate it, valve actuating mechanism controlling the motion of an air admission valve of the compressor and having adjustable members for varying the motion of the valve and which said mechanism when in operation tends to move alternately in opposite directions, a cylinder G', having fluid admission ports at both ends controlled by non-return valves, and exit ports also connected to both ends, and controlled by means which closes both in normal position and opens one or the other in accordance with the motion imparted to it, a piston G, working in cylinder G', and connected to the adjustable members of the admission valve actuating mechanism of the compressor, means adapted to shift its position with the variations of pressure in the receiver of the compressor, and mechanism whereby the motions of the variable pressure device aforesaid is transmitted to the device controlling the exit ports of the cylinder G', so as to open one or the other of said exit ports as the pressure in the receiver varies above or below the normal.

7. In combination with an air compressor or blower and a gas engine connected to actuate it, valve actuating mechanism controlling the motion of an air admission valve of the compressor and having adjustable members for varying the motion of the valve and which said mechanism when in operation tends to move alternately in opposite directions, a cylinder G', having fluid admission ports at both ends controlled by non-return valves, and exit ports also connected to both ends, and controlled by a valve which closes both in normal position and opens one or the other in accordance with the motion imparted to it, a piston G, working in cylinder G', and connected to the adjustable members of the admission valve actuating mechanism of the compressor, means adapted to shift its position with the variations of pressure in the receiver of the compressor, and a valve actuating lever, as H', connected to the exit valve of cylinder G', and connected at its ends with the shifting mechanism actuated by the pressure in the receiver and with a part shifting its position with the movements of piston G, as described, whereby an increase of pressure in the receiver will by shifting the exit valve of cylinder G', permit the piston G, to move in a direction corresponding to an adjustment of the admission valve mechanism which will cause the valve to defer its closing, and whereby the movement of piston G, will in

turn return the exit valve of cylinder G', to position to close both ports and thereby arrest the motion of the piston.

8. In combination with an air compressor or blower and a gas engine connected to actuate it, valve actuating mechanism controlling the motion of an air admission valve of the compressor and having adjustable members for varying the motion of the valve and which said mechanism when in operation tends to move alternately in opposite directions, a governor regulating the admission to the gas engine, means for varying the action of said governor, a cylinder G', having fluid admission ports at both ends controlled by non-return valves, and exit ports also connected to both ends, and controlled by means which closes both in normal position and opens one or the other in accordance with the motion imparted to it, a piston G, working in cylinder G', and connected to the adjustable members of the admission valve actuating mechanism of the compressor, and to the means for varying the action of the governor and means adapted to shift its position with the variations of pressure in the receiver of the compressor and mechanism whereby the motions of the variable pressure means aforesaid are transmitted to the device controlling the exit ports of the cylinder G', so as to open one or the other of said exit ports as the pressure in the receiver varies above or below the normal.

9. In combination with an air compressor or blower and a gas engine connected to actuate it, valve actuating mechanism controlling the motion of an air admission valve of the compressor and having adjustable members for varying the motion of the valve and which said mechanism when in operation tends to move alternately in opposite directions, a governor regulating the admission to the gas engine, means for varying the action of said governor, means for supplying water to jacket the gas engine, a valve to regulate said water supply, a cylinder G', having fluid admission ports at both ends controlled by non-return valves, and exit ports also connected to both ends and controlled by means which closes both in normal position and opens one or the other in accordance with the motion imparted to it, a piston G, working in cylinder G', and connected to the adjustable members of the admission valve actuating mechanism of the compressor and to the means for varying the action of the governor and the water supply regulating valve, means adapted to shift its position with the variations of pressure in the receiver of the compressor, and mechanism whereby the motions of the variable pressure device aforesaid is transmitted to the device controlling the exit ports of the cylinder G', so as to open one or the other of said exit ports as the pres-

sure in the receiver varies above or below the normal.

10. In combination with an air compressor or blower and a gas engine connected to actuate it, an adjustable valve actuating mechanism arranged to vary the time of closing its valve in accordance with its adjustment, an air admission valve for the compressor actuated through said adjustable valve mechanism, a governor controlling the admission to the gas engine cylinder, means for varying the action of said governor, and means connecting an adjustable member of the admission valve actuating mechanism of the compressor with the mechanism for varying the action of the governor as described.

11. In combination with an air compressor or blower and a gas engine connected to actuate it, an adjustable valve actuating mechanism arranged to vary the time of closing its valve in accordance with its adjustment, an air admission valve for the compressor actuated through said adjustable valve mechanism, a governor controlling the admission to the gas engine cylinder, means for varying the action of said governor, a water conduit leading to the jacket of the gas engine, a valve for regulating the water supply and means connecting an adjustable member of the admission valve actuating mechanism of the compressor with the mechanism for varying the action of the governor and with the water supply, as described.

12. In combination with an air compressor or blower and a gas engine connected to actuate it, a link F³, having means for imparting a circular motion to one end and its other end guided by a swinging link F⁵, an adjustable lever F⁸, supporting the pivot of link F⁵, an air admission valve connected with and actuated by link F³, a governor for the admission valve of the gas engine, means for varying the action of said governor, mechanism connecting said means with lever F⁸, so as to vary the action of the governor as the closing of the air admission valve of the compressor varies and means for adjusting the lever F⁸.

13. In combination with an air compressor or blower and a gas engine connected to actuate it, a link F³, having means for imparting a circular motion to one end and its other end guided by a swinging link F⁵, an adjustable lever F⁸, supporting the pivot of link F⁵, an air admission valve connected with and actuated by link F³, a governor for the admission valve of the gas engine, means for varying the action of said governor, mechanism for connecting said means with lever F⁸, so as to vary the action of the governor as the closing of the air admission valve of the compressor varies, a cylinder G', having non-return admission ports and exhaust ports controlled by a valve, as G³, normally closing both and adapted to open one or the other as it is shift-

ed in different directions, a piston G, connected to lever F^s, a link H', connected to valve G^s, a connection from one end of link H' to lever F^s, and means connected to the other end of link H', for shifting it.

14. In combination with an air compressor or blower and a gas engine connected to actuate it, a link F^s, having means for imparting a circular motion to one end and its other end 10 guided by a swinging link F^s, an adjustable lever F^s, supporting the pivot of link F^s, an air admission valve connected with and actuated by link F^s, a governor for the admission valve of the gas engine, means for varying 15 the action of said governor, mechanism connecting said means with lever F^s, so as to vary the action of the governor as the closing of the air admission valve of the compressor varies, a cylinder G', having non-return admission 20 ports and exhaust ports controlled by a valve, as G^s, normally closing both and adapted to open one or the other as it is shifted in different directions, a piston G, connected to lever

F^s, a link H', connected to valve G^s, a connection from one end of link H', to lever F^s, 25 and means connected to the other end of link H', for shifting it, said means being in turn actuated by the varying pressure in the receiver of the compressor.

15. In combination with an air compressor 30 or blower and a gas engine connected to actuate it, a valve, controlling the admission to the gas engine, a reciprocating hook for opening said valve, an adjustable stop for detaching said hook and permitting the valve to 35 close, a governor connected to adjust the stop, an adjustable weight arranged to vary the action of the governor, and means actuated by the variations in pressure in the receiver of the compressor for adjusting said weight.
